William Richard

ATTORNEY

UNITED STATES PATENT OFFICE.

JOHN KOMETTER, JR., OF MILWAUKEE, WISCONSIN.

AUTOSCOPE.

1,338,738.

Specification of Letters Patent.

Patented May 4, 1920.

Application filed February 28, 1919. Serial No. 279,759.

To all whom it may concern:

Be it known that I, JOHN KOMETTER, Jr., a citizen of the United States, residing at Milwaukee, county of Milwaukee, and State 5 of Wisconsin, have invented certain new and useful Improvements in Autosopes, of which the following is a specification.

This invention relates to improvements in autosopes, or mirror supports as applied 10 to vehicles, whereby the operator is enabled to obtain a view of objects on either side and in advance of the vehicle body, even if remote and screened by intervening walls or other obstructions preventing direct 15 vision.

The principal object of the invention is to provide a plurality of mirrors or reflecting surfaces at the extreme front of 20 the vehicle, so as to project the image of objects at the sides to other mirrors which are readily seen from within the vehicle, for instance cars approaching intersecting crossings or entering the street from 25 buildings, etc., thereby materially aiding in avoiding collision and consequent damages.

These and other like objects are attained by the novel construction and combination 30 of parts hereinafter described and shown in the accompanying drawings, forming a material part of this disclosure, and in which:—

Figure 1 is an illustrative plan view showing a typical street scene and indicating the 35 application of the invention.

Fig. 2 is an enlarged plan view showing the arrangement of the mirrors relative to the vehicle and indicating diagrammatically the optical arrangement of the same.

Fig. 3 is a rear view of the same, and

Fig. 4 is a side elevational view showing a modified mounting for the mirrors.

Fig. 5 is a detail sectional view showing a device which may be applied to lower the 45 mirrors when desired.

In the view shown in Fig. 1, a conventional type of car, designated by the numeral 10, is indicated as passing over the level surface of a street 11, the car being close to 50 the sidewalk 12, at the opposite side of which is a building, indicated by the walls 13, partially screened by trees or shrubbery 15, the building being for instance, a garage containing other cars 16 and 17, the last being 55 shown in position to pass out from the

door of the garage immediately into the path of the vehicle 10; assuming both cars to be moving, a collision is obviously imminent and to prevent such occurrences is the main object of this invention.

In order to obtain a view from the car 10, prior to its forward movement, so as to be in the path of another vehicle moving at right angles thereto, as indicated, there is secured to the tubular filling nozzle 20, of the radiator 21, below the screw cap 22, a split clamp band 23, formed in two equal parts and secured by a bolt 24 at one end, while the other, elongated ends of the band are similarly clamped by a pair 60 of bolts 25, which also pass through a pair of support strips 26, the same being turned at an angle vertically upward, as at 27, and spread, forming the elements of a fork 28, their outer ends 29 being turned rearward, 65 presenting diverging angular supports to which are secured the backs of the frames 30, containing mirrors or highly polished reflecting surfaces 31, the same being directed diagonally outward, and adapted to 70 reflect images from other mirrors 32, contained in frames 33, carried by supports 34, the same being angular continuations of bars 35 converging at their inner ends and half between the fork elements 28 by rivets 36.

It is to be understood, however, that the support elements may be flat metallic bars or strips, tubes or suitable wire rods, and that the mirrors may be round or rectangular as shown, as preferred.

Thus objects, as indicated by the letter A are reflected from the mirrors 31 to the mirrors 32, and from thence to the eye of the operator taking observations from a point 90 indicated by the letter B.

In the modification shown in Fig. 4, the mirror 40 is secured in a holder or frame 41, attached by the hinge elements 42, to a downturned angular support 43 formed with 100 the support bar 44, engaged with the elements 29 or 35, the mirror 40 being inclinable on the hinge 42, due to an adjusting screw 45, threaded into the angular support element 43 and movable by a head 46, the 105 point of the screw being engaged in the mirror frame by suitable connections 47, thus providing means whereby the mirrors may be inclined from a vertical plane so as to reflect the objects in an effective manner.

In Fig. 5 I have indicated the bar 26 as pivotally connected as at 50 to the collar 23 and having a bayonet slot 51 adapted to receive a bolt 52 passing through a slot 53 in the ears of the collar 23, this bolt being tightened by a wing nut 54. A similar arrangement may be applied to the parts 28 and 35. With this arrangement the mirrors may be lowered when desired, as to permit 10 of filling the radiator.

From the foregoing it will be seen that an effective device has been presented whereby collisions may be forestalled and avoided by reason of any approaching objects from 15 either side being clearly disclosed to the operator of the car, without effort.

Having thus disclosed my invention, in a manner which is to be regarded as descriptive rather than limitative of the device, 20 which obviously may be made in embodiments including many minor changes without departing from its general scope, what I claim as new, and desire to secure by Letters Patent is:—

25 1. In a device of the class described, a split collar attached to the radiator nozzle of an automobile, a pair of brackets extending horizontally forward from said collar, the ends of said brackets being bent back to-
30 ward said collar, vertical mirrors on the ends of said brackets, a second pair of horizontal brackets secured between said first named brackets and extending forward therefrom, the ends thereof being bent back
35 toward said collar, and vertical mirrors on the ends of said second-named brackets.

2. In a device of the class described, a split collar attached to the radiator nozzle of an automobile, a pair of brackets extending horizontally forward from said collar, 40 the ends of said brackets being bent back toward said collar, vertical mirrors on the ends of said brackets, a second pair of horizontal brackets secured between said first named brackets and extending forward 45 therefrom, the ends thereof being bent back toward said collar, and vertical mirrors on the ends of said second-named brackets, said first named brackets being pivotally attached to said collar.

50 3. In a device of the class described, a split collar attached to the radiator nozzle of an automobile, a pair of brackets extending horizontally forward from said collar, the ends of said brackets being bent back 55 toward said collar, vertical mirrors on the ends of said brackets, a second pair of horizontal brackets secured between said first named brackets and extending forward therefrom, the ends thereof being bent back 60 toward said collar, and vertical mirrors on the ends of said second-named brackets, said first named brackets being pivotally attached to said collar, said first named brackets each having a slot formed therein, and 65 said collar having a bayonet slot therein, and a pin adapted to engage in said slots to lock the brackets to the collar.

In testimony whereof I have affixed my signature this 5th day of February, 1919. 70

JOHN KOMETTER, JR.
